UNITED STATES PATENT OFFICE.

CLIFTON H. BEACH, OF SALTSBURG, PENNSYLVANIA.

DESIGN FOR A BOTTLE.

SPECIFICATION forming part of Design No. 27,261, dated June 29, 1897.

Application filed May 10, 1897. Serial No. 635,940. Term of patent 14 years.

To all whom it may concern:

Be it known that I, CLIFTON H. BEACH, a citizen of the United States, and a resident of Saltsburg, in the county of Indiana and State of Pennsylvania, have invented and produced a new and original Design for Bottles; and I do hereby declare that the following is a full, clear, and exact description of the invention, which will enable others skilled in the art to 10 which it appertains to make and use the same, reference being had to the accompanying drawings, which form a part of this specification.

My design relates to bottles; and it consists 15 in the peculiar configuration given thereto, which imparts an ornamental and attractive appearance to the bottle.

In the accompanying drawings, Figure 1 is 20 an elevation of a bottle made in accordance with my design. Fig. 2 is a horizontal section on the line x x , Fig. 1.

In the said drawings the reference-numeral 1 designates the body of the bottle, compris-

ing the four sides inclined at acute angles to the vertical plane thereof and having a flat 25 bottom. The bottle is formed with a cylindrical neck 3, the upper end or mouth of which is formed with a beveled rim 4. The upper ends of said sides just below the neck are formed on curved lines, as seen in Fig. 1, and 30 the bottle is flattened vertically at the longest diameter.

A bottle constructed as above will be very ornamental and present a neat and attractive appearance. 35

What I claim is—

The design for a bottle herein shown and described.

In testimony that I claim the foregoing as my own I have hereunto affixed my signature 40 in presence of two witnesses.
